TOILET CASE

Filed Dec. 18, 1920

Fig. 1.

Inventor:
Morris W. Askin

UNITED STATES PATENT OFFICE.

MORRIS W. ASKIN, OF WASHINGTON, DISTRICT OF COLUMBIA.

TOILET CASE.

Application filed December 18, 1920. Serial No. 431,765.

To all whom it may concern:

Be it known that MORRIS W. ASKIN, a citizen of the United States, residing at Washington, in the District of Columbia, has invented certain new and useful Improvements in Toilet Cases, of which the following is a specification.

This invention relates to toilet cases, and the primary object of the invention is to provide an improved case for containing a toothbrush and other toilet articles or the like, in a clean and sanitary condition, and which, owing to its small and compact nature, is particularly adapted for travelers, and may be conveniently carried in the user's pocket or traveling bag.

Another object of the invention is to provide in a toilet case means for receiving and holding a tube of dental cream, in such manner that upon opening of the case the tube may be projected outwardly therefrom a predetermined distance, so as to permit the contents thereof to be conveniently expelled upon the toothbrush, thus obviating the necessity for removing the tube of cream from the case; the closing of the case acting to hold the tube in its retracted position therein, and thus to retain it in spaced relation to the walls of the case, thereby preventing the interior of the case from becoming soiled by the paste, whether the retaining cap of the tube is on or off.

A still further object of the invention is to provide in a toilet case a separable paste tube carrier which will materially lessen the inconvenience of handling the tube of paste, and will keep same in good condition for use, it being necessary merely to press the tube against the plate of the carrier, or, if the carrier is removed from the cabinet, to press the plate and tube between the fingers to force out the paste.

A still further object of the invention is the provision of a toilet case which lends itself readily to manufacture from a variety of materials, such as glass, ivory, pyraline, celluloid or metal, and, if of the latter, it may be plated as desired.

The invention consists in a toilet case adapted to contain a toothbrush, tube of tooth paste, and mirror or other toilet

articles, the tube of tooth paste being so mounted within the case as to be operable while supported thereby, or removed therefrom, as desired, means being provided for holding the tube in such manner that it may be projected from within the case when the case is opened and may be retracted and held in spaced relation within the walls of the case when the latter is closed, all as I will proceed now to explain and finally claim.

In the accompanying drawings illustrating the invention, in the several figures of which like parts are similarly designated,

Figure 1 is a top view of the improved case, showing the cover in its open position.

Figure 2 is a side elevation of the same with the cover in its closed position.

Figure 3 is a transverse section taken on line 3—3 of Figure 2.

Figure 4 is a fragmentary longitudinal section illustrating the means for detachably holding the tube of tooth paste in position.

Figure 5 is an end elevation of the body of the case.

Figure 6 is an end elevation of the cover of the body.

Figure 7 is a fragmentary longitudinal section through the same, illustrating the means for detachably holding the tooth paste tube carrier in position.

Figure 8 is a fragmentary longitudinal section through the toilet case, showing the cover in an opened position, and Figure 9 is a detailed perspective view of the improved trench mirror.

Referring to the drawings in detail, the numeral 10 indicates generally the improved toilet case which includes the body 11 and the hinged cover 12, the body 11 being of a substantially elongated rectangular construction and consisting of the bottom wall 13, the side walls 14 and the end walls 15 and 16. The cover 12 includes the top plate 17, the side flanges 18, and the end flanges 19 and 20. The case is preferably made of a non-corrosive and non-rusting material, and may be suitably plated so as to present a pleasing appearance. The cover 12 has secured thereto, in any preferred manner, a longitudinally extending plate 21, the side edges of which are bent inwardly towards

each other to provide guide flanges 22. These guide flanges slidably receive the tooth paste tube carrier 23, which carrier consists of a substantially flat body the forward end of which is cut and bent to provide an arcuate resilient jaw 24 which is adapted to hold the tube of tooth paste 25 in position. The opposite end of the carrier 23 has connected thereto, as by means of a pivot pin 25, a swinging plate 26, the inner end of which is bent to provide a substantially V-shaped resilient jaw 27, adapted to receive the folded end of the tube of tooth paste 25. The outer ends of the flanges 22 are flared outwardly and upwardly, as at 28 (see Figs. 1 and 8), and this permits the convenient removal from and placing of the carrier on the plate 21.

When the cover is in its open position, the carrier 23 will slide towards the free end thereof and engage the end flange 20, which limits its sliding movement. The end flange 20 is provided with a cut out portion 29 which permits the forward end of the tube 25 to slide beyond the end of the case. When it is desired to remove the carrier from the case 10, it is necessary to lift the forward end of the carrier above and slide it beyond the end flange, 20, this being permitted by the raised and flared portion 28 of the flanges 22. The inner end of the carrier 23 is provided with an opening 30 which permits the carrier to be hung upon a suitable nail or the like when the case is not in use. The end wall 16 of the body 11 is notched, as at 31, and the central portion of the notched section is provided with an upwardly and inwardly extending tongue 32. This tongue 32 is adapted to engage in the opening 30 when the cover 12 is in its closed position, so as to preclude accidental sliding movement of the carrier when the case remains closed to thus hold the end of the tube of paste spaced from the end wall of the case, thereby preventing the soiling of the case, whether the retaining cap of the tube is on or off.

It is to be understood that the tube of tooth paste is of the ordinary or any preferred construction, and that when it is desired to place a tube of tooth paste in position, the plate 26 is swung on the pivot pin 25 until the same is positioned at right angles to the longitudinal center of the plate and the folded end of the paste tube in the resilient jaw 27. The plate 26 is then swung back to its normal position and the forward end of the tube is placed under the jaw 25.

The body 11 receives a trench mirror 34, and a tooth brush 35. The trench mirror 34 is of a suitable shape so as to conveniently fit in the case, and is provided with an opening 36 whereby it may be hung up if desired. One longitudinal edge of the mirror is provided with a plurality of upstanding

tongues 37 which are adapted to frictionally engage the handle of the tooth brush. The provision of these tongues forms an efficient means for holding the tooth brush and trench mirror in position against accidental displacement.

The cover 12 may be hingedly connected to the body in any preferred manner, and as shown, a pair of depending ears 38 are formed on the rear end of the cover and these ears receive the transversely extending pivot pin 39.

If so desired, the side walls 14 of the body 11 may be suitably corrugated as indicated by the numeral 40 in Fig. 2, so as to permit the entrance of fresh air into the case and thus insure the effective drying of the tooth brush.

A plate 41 is connected to one end of the body for swinging movement and this plate is provided with a key hold slot 42 which permits the convenient hanging up of the case when desired.

From the foregoing description, it will be seen that I provide an improved toilet case of simple and durable construction which, owing to its sanitary features will appeal to the public.

Changes in details of construction and arrangement of parts are contemplated as within the spirit of the invention and the scope of the following claims:

1. In a toilet case, a body portion, a lid hingedly connected therewith, a slidable tooth-paste tube carrier, and means on said lid and carrier for allowing sliding of said carrier to projected and retracted position and for locking it in retracted position when said lid is closed.

2. A toilet case comprising a body having a hinged lid, a guide secured longitudinally of the lid, a carrier plate slidably and detachably associated with the guide, a resilient clip carried by the forward end of the plate arranged to engage a tube of tooth paste, a plate connected to the carrier plate adjacent to its inner end for swinging movement, and a resilient jaw formed on said hinged plate arranged to engage the folded portion of the tube of tooth paste.

3. A toilet case having a body, a lid hingedly connected to the body at one end thereof, a longitudinally extending plate secured to the inner surface of the lid, inwardly extending angular guide flanges formed on said plate, a carrier plate slidably carried by the flanges, an inwardly extending flange formed on said lid arranged to limit the outward sliding movement of the carrier plate, the outer ends of said guide flanges being flared to permit of the outer end of the carrier plate being lifted above the end flange of the lid, the inner end of said carrier plate having an opening formed therein, and a resilient spring tongue formed

on the rear wall of the body, arranged to engage in said opening to prevent accidental sliding movement of the carrier plate

the trench mirror arranged to frictionally engage the tooth brush in said case and to hold the trench mirror and tooth brush 10 against movement in relation to each other.

4. In a toilet case, the combination of a body having a hinged lid, a trench mirror arranged in the body, a tooth brush arranged in the body, and resilient means formed on

In testimony whereof I affix my signature.

MORRIS W. ASKIN.
